[57] CLAIM

The ornamental design for clothes and shoe holder for clothes dryer, as shown.

DESCRIPTION

FIG. 1 is a front elevational view of the clothes and shoe holder for clothes dryer showing my design;

FIG. 2 is a rear elevational view thereof;

FIG. 3 is a side elevational view thereof, the opposite side being a mirror image; and,

FIG. 4 is a perspective view thereof, shown with the straps in an alternate position.

The broken lines shown along the border of the pouch and at both ends of the straps represent conventional stitching.

The crosshatched pattern which is partially shown for ease of illustration, represents a mesh fabric and is understood to repeat throughout the areas indicated.
